UNITED STATES PATENT OFFICE.

JAMES M. SEYMOUR, JR., OF NEWARK, NEW JERSEY.

HYGROMETER.

1,184,140.

Specification of Letters Patent.

Patented May 23, 1916.

Application filed January 26, 1915. Serial No. 4,424.

To all whom it may concern:

Be it known that I, JAMES M. SEYMOUR, Jr., a citizen of the United States, residing at Newark, in the county of Essex and State 5 of New Jersey, have invented certain new and useful Improvements in Hygrometers; and I do hereby declare the following to be a full, clear, and exact description of the invention, such as will enable others skilled in 10 the art to which it appertains to make and use the same, reference being had to the accompanying drawings, and to characters of reference marked thereon, which form a part of this specification.

15 The present invention relates, generally, to improvements in that class of meteorological instruments known as hygrometers which are used for ascertaining the percentage of humidity in the atmosphere; and, the 20 present invention, has reference, more particularly, to a registering hygrometer from which the conditions or percentage of atmospheric humidity can be read directly and at 25 a glance without necessity of calculation and regardless of temperature.

My present invention, therefore, has for its principal object to provide a hygrometer-instrument of simple character and construction which is provided with a readable indicating or registering means, from which a direct and accurate reading of the percentage of humidity in the atmosphere at any time may be gained without necessity of calculating that percentage, as is necessary to 35 be done with the old style wet and dry bulb thermometer-hygrometer.

A further object of the present invention is to provide a novel construction and arrangement of hygrometer instrument which 40 will accurately indicate or register the percentage of humidity in the atmosphere under all conditions and changes of atmospheric temperature, the instrument being so constructed that changes in temperature do not 45 in any way affect or interfere with its operations in indicating atmospheric conditions of humidity.

Other objects of the present invention, not at this time more particularly enumerated, 50 will be clearly understood from the following detailed description of the said invention.

With the various objects of the present invention in view, the said invention consists, 55 primarily, in the novel hygrometer herein-after set forth; and, furthermore, the inven-

tion consists in the novel arrangements and combinations of the several devices and parts comprising the same, as well as in the details of the construction of said parts, all of 60 which will be more fully described in the following specification, and then finally embodied in the clauses of the claims which are appended to and which form an essential 65 part of said specification.

The invention is clearly illustrated in the accompanying drawings, in which:—

Figure 1 is a plan or top view of a novel hygrometer, showing one embodiment of the invention, and made according to and embodying the principles of the present invention. Fig. 2 is a transverse section of the same, said section being taken on line 2—2 in said Fig. 1, looking in the direction of the arrow *x*. Fig. 3 is another transverse section of the same, taken on line 3—3 in said Fig. 1, also looking in the direction of the arrow *x*. Fig. 4 is still another transverse section of the device, said section being taken on line 4—4 in said Fig. 1, also looking 75 in the direction of the arrow *x*. Fig. 5 is an enlarged detail plan view of the indicating end of the hygrometer, illustrating the construction and operation of the novel indicating mechanism. Fig. 6 is an elevation of an 80 indicating hygrometer, indicating a modification of the invention, the same still embodying, however, the principles of the present invention.

Similar characters of reference are employed in all of the hereinabove described views, to indicate corresponding parts.

Referring now to the said drawings, the reference-character 1 indicates a suitable base upon which the novel hygrometer may 90 be suitably mounted, said hygrometer comprising a rod 2 and a rod 3, both of equal length and mounted to be spaced apart and parallel to each other. The said rods 2 and 3 may be of any length desired, and may 95 be constructed of metal, hard-rubber, or in fact any material capable of contraction and expansion.

Adjacent ends of the said parallel rods 2 and 3 may be suitably tied or clamped together, preferably by means of a transversely disposed and suitably constructed clamping member, as 4, which rigidly connects the said rods and serves to hold such ends of the rods immovable, relatively one 105 to the other, or from moving independently of each other at such ends.

The reference-character 5 indicates a suitably formed tank or pan of a length corresponding approximately to the length of the rod 2, said tank or pan being adapted to contain water, or any other desired fluid. Connected with and extending transversely across said tank or pan, and extending beyond one side thereof, are a plurality of suitably constructed supporting bridges or spreader-members, as 6, the same being provided with pairs of aligned grooves or channels 7 through which the respective rods 2 and 3 extend. These bridges or spreader-members 6 not only support the rods 2 and 3, so that the same are free to move longitudinally thereon under the force of their expansion or contraction, but the grooves 7 thereof tend also to keep the rods properly spaced and parallel, and maintain the same against lateral movement, bending, buckling, or other undesired distortion, so that the movement caused by their expansion or contraction will be controlled and directed or permitted only along lines longitudinal to their axes.

Suitably secured to the free or opposite ends of said rods 2 and 3, so that the same will face each other, are toothed racks 8 and 9, and suitably supported and rotatably mounted between said racks, and engaged on opposite sides by the teeth thereof, is a pinion 10. This pinion may be provided with upper and lower marginal flanges, as 11 and 12, which prevent the disengagement of the pinion from its operative relation to the said racks 8 and 9. Connected with said pinion 10 is a forwardly projecting or extending needle or indicating pointer 13, the free end of which is adapted to register above and is adapted to move or oscillate in the arc of a circle across a fixed graduated scale-member, as 14, the latter being supported or secured in its fixed relation by any suitable means. The graduations or marks 15 of said scale-member are adapted to indicate percentages of humidity in the atmosphere.

Suitably twined or woven around the rod 2, or otherwise secured and mounted thereon, is a medium, body or strip 16 of lamp wicking, felt, or other suitable porous material, adapted by capillary attraction to take up or soak up water or other fluid. This porous strip 16 is so wound or related to the rod 2, that while supported in contact therewith, portions 17 of the said strip hang down therefrom, and are submerged in the water contained in the tank or pan 5 which, as has been stated, is located beneath said rod 2. By means of this porous medium or strip 16, the water in the tank or pan 5 is brought into contact with the rod 2, and the evaporation of water from that portion of the porous medium or strip, exterior of the water tank or pan 5 and in contact with the

rod 2, chills said rod 2, so that said rod contracts, while the rod 3, which is not exposed to such chilling action, but merely to the ordinary atmospheric temperature, does not contract. Consequently there is a greater longitudinal movement of the rod 2 than of the rod 3, which may not even move at all, and such effects causing and producing a differential movement of the racks 8 and 9 connected with said rods which correspondingly rolls or rotates the pinion 10 as will be clearly evident and thereby causes a deflection or oscillation of the needle or indicating pointer 13 from its normal or zero position, so that the same moves over the scale-member 14 and registers with one of the graduations, and thereby immediately designates the percentage of humidity corresponding to the particular relative movement of the rods 2 and 3, and is readable in degrees without any further calculations on the part of the party using the instrument.

It is evident, that when both rods 2 and 3 are subjected to atmospheric temperature alone, (that is when the rod 2 is not chilled,) they will both expand and contract equally, each rod carrying its respective rack forward or backward, so that both racks travel together, and the pinion 10 is not rotated, the only effect upon the needle or pointer carried thereby being to carry the same slightly forward or backward over the scale-member 16 without deflection or oscillation to either side of the normal or zero-point, as will be clearly understood from an inspection of the figures of the drawings.

It will thus be apparent, that changes in atmospheric temperature when the device is operating, (that is when the rod 2 is chilled), providing there are no changes in the percentage of humidity, do not affect the oscillated position of the needle or indicating pointer relative to the scale-member, but a change in temperature which involves a change in the percentage of humidity, or a change in the percentage of humidity not involving a change of temperature, will be indicated upon the scale-member by a corresponding shifted position of the needle or indicating pointer.

The degree of chill produced in the rod 2 depends upon the rapidity and amount of evaporation from the porous medium or strip 16, and this evaporation is in proportion to the humidity in the atmosphere. In other words, the dryer the atmosphere, the more violent is the evaporation; and, the more violent the evaporation, the greater will be the chilling effect upon the rod 2, and the greater its contraction relative to the rod 3. It is therefore apparent, that once the amount of fluctuation of the needle or indicating-pointer thus produced under given or known conditions of humidity is ascertained and its place marked on the

scale-member by the graduations 17, subsequent readings direct from the scale-member, as indicated by the needle or indicating pointer, will ever after give the percentage 5 of humidity without the necessity of any additional calculations.

Referring now to Fig. 6 of the drawings, I have illustrated therein a modified construction of hygrometer, made according to 10 and embodying the principles of the present invention. In this construction I employ, in place of the rods 2 and 3, a pair of mercury columns, as 18 and 19, suitably secured in fixed parallel relation to each other. The 15 upper end of the tubes containing the mercury, also contain air or some suitable volatile gas, and connected in communication with the air or gas are suitably constructed diaphragm-members 20 and 21, which as 20 will be evident, are adapted to expand or contract under the action or influence of the air or gas contained in said tubes. Secured to said diaphragms are connecting rods, as 22 and 23, the respective free ends of which 25 are pivotally connected with the butt or beam 24 of a needle or indicating-pointer 25, adapted to be deflected or oscillated with relation to a suitable scale-member 26. As will be seen from the drawing, that the bulb 30 of the mercury column 18 is subjected to normal atmospheric temperature, and that the bulb of the mercury column 19 is situated adjacent to a suitable tank or pan 27 containing water, a wick or wicks of porous 35 substance 28 being wrapped around the bulb of the said mercury column 19, and the ends of said wick or wicks being submerged in the water of said tank or pan 27. Evaporation 40 of the water from the wick or wicks surrounding the bulb of the column 19 chills the mercury column and contracts the same, thereby reducing the compression of the air or other gas above the mercury and in consequence contracting the diaphragm 21, 45 whereas the air or gas in the column 18 remains compressed by the position of the mercury column as determined by the temperature of the atmosphere. It will be apparent, that the indicating needle or pointer 50 25 will be rocked or oscillated by the different heights attained by the connecting-rods as determined by the differential movement of the diaphragms to which they are respectively connected, and consequently said 55 needle or pointer will indicate in degrees, by reference to said scale-member, the percentage of humidity in the atmosphere. It will be clearly evident, that while there are structural differences between this modified 60 construction of hygrometer and the construction previously described, the method and principle of operation are essentially the same, the difference residing merely in the character of the expanding and contracting element, and the means for trans-

mitting the differential movements thereof to the needle or pointer required by the particular character of the expanding and contracting elements used.

I am aware therefore, that some changes 70 may be made in the general arrangements and combinations of the several devices and parts, as well as in the details of the construction of the said parts, without departing from the scope of the present invention 75 as set forth in the foregoing specification, and as defined in the claims appended thereto. Hence, I do not limit my invention to the exact arrangements and combinations of the various devices and parts as 80 herein set forth, and as illustrated in the accompanying drawings, nor do I confine myself to the exact details of the construction of the said parts.

I claim:

1. A hygrometer comprising a pair of parallel and spaced rod-members capable of expansion and contraction, means retaining the adjacent ends of said rod-members at one end fixed against movement due to 90 differential expansion or contraction of said rod-members, the opposite ends of said rod-members being free and capable of movement due to differential expansion or contraction of said rod-members, means for 95 chilling one of said rod-members by evaporation, an indicating needle, a scale-member with which said indicating needle co-operates, and means for transmitting the movement caused by the differential of ex- 100 pansion or contraction of said rod-members to the indicating needle to oscillate the same.

2. A hygrometer comprising a pair of rods capable of expansion and contraction, 105 clamp-means interconnected with the adjacent ends of said rods at one end to retain said ends against movement due to differential expansion or contraction of said rods, the opposite ends of said rods being free 110 and capable of movement due to differential expansion or contraction of said rods, rack-members carried by the free ends of said rods, a pinion engaged by said rack-members, an indicating needle connected 115 with said pinion, a scale-member with which said indicating needle co-operates, and means for chilling one of said rods by evaporation to produce a differential expansion or contraction of said rods.

3. A hygrometer comprising a pair of rods capable of expansion and contraction, a clamp-means interconnected with the adjacent ends of said rods at one end to retain said ends against movement due to differential expansion or contraction of said rods, the opposite ends of said rods being free 125 and capable of movement due to differential expansion or contraction of said rods, rack-members carried by the free ends of 130

4
 said rods, a pinion engaged by said rack-members, an indicating needle connected with said pinion, a scale-member with which said indicating needle coöperates, and means 5 for chilling one of said rods by evaporation to produce a differential expansion or contraction of said rods, comprising a tank for water or other liquid beneath said rod to be chilled, and wicking partially sub- 10 merged in the contents of said tank and maintained in contact with said rod.

4. A hygrometer comprising a pair of rods capable of expansion and contraction, clamp-means interconnected with the adjacent ends of said rods at one end to retain said ends against movement due to differential expansion or contraction of said rods, the opposite ends of said rods being free and capable of movement due to differential expansion or contraction of said rods, rack-members carried by the free ends of said rods, a pinion engaged by said rack-members, an indicating needle connected with said pinion, a scale-member with 15 which said indicating needle coöperates, means for supporting said rods parallel to and spaced from each other, means for preventing lateral movement, bending, buckling or distortion of said rods, and 20 means for chilling one of said rods by evaporation to produce a differential expansion or contraction of said rods.

5. A hygrometer comprising a pair of rods capable of expansion and contraction, 25 clamping means interconnected with the adjacent ends of said rods at one end to retain said ends against movement due to differential expansion or contraction of said rods,

the opposite ends of said rods being free and capable of movement due to differential 40 expansion or contraction of said rods, means for supporting said rods parallel to and spaced from each other, means for preventing lateral movement, bending, buckling or distortion of said rods, means for chilling one of said rods by evaporation in proportion to the moisture in the surrounding 45 atmosphere, a mechanical device coupled with said rods operated by the differential expanding or contracting movements thereof for indicating the amount of such movement for the purposes specified, and a scale with which said mechanical device operates.

6. In a hygrometer a pair of rods capable of expansion and contraction, clamp-means for retaining adjacent ends of said rods at one end against movement due to differential expansion and contraction of said rods, the opposite ends of said rods being free and capable of movement due to differential expansion and contraction of said rods, means for chilling one of said rods by evaporation to produce a differential expansion or contraction of said rods, and mechanism connected with the free ends 60 of said rods for the transmission of motion produced by said expansion or contraction thereof.

In testimony, that I claim the invention set forth above I have hereunto set my 70 hand this 19th day of January, 1915.
